UNITED STATES PATENT OFFICE.

NILS F. HAGSTRÖM, OF BROOKLYN, NEW YORK.

SECTIONAL SHOE-LAST.

SPECIFICATION forming part of Letters Patent No. 703,958, dated July 1, 1902.

Application filed April 11, 1901. Serial No. 55,322. (No model.)

To all whom it may concern:

Be it known that I, NILS F. HAGSTRÖM, a citizen of the United States of America, and a resident of the borough of Brooklyn, New York city, and State of New York, have invented certain new and useful Improvements in Sectional Shoe-Lasts, of which the following is a specification.

My invention relates to improvements in shoe-lasts made in sections adapted to facilitate removal of the last from the shoe when completed by removing it in sections; and it consists of the improved construction whereby the same is simplified and cheapened and the operation improved, as hereinafter described, reference being made to the accompanying drawings, in which—

Figure 1 is a longitudinal vertical section of my improved last. Fig. 2 is a transverse section on line 2 2, Fig. 1; and Fig. 3 is a plan view.

The last is first made solid in the usual way. Then the instep portion *b* is sawed out of the main or sole part *a* on the lines *c d*, and the heel part *e* is sawed off from sole part *a* on the line *f*, said line *f* intersecting line *c* at a point *g*, so that the rear extremity *h* of part *b* overlaps the upper end of heel part *e* and line *f* slopes rearwardly from the intersecting point *g* to the rear extremity of the lower portion of the heel.

A recess *i* is formed in the face of part *a*, from which the heel part *e* of the last is cut, said recess extending from near the bottom of part *a* to the surface of said part on which the instep *b* rests and along the same a short distance toward the toe, as shown at *i*. An angle-plate of metal *j j'*, provided with a dovetail groove *k* lengthwise in the part *j*, is fitted in said groove *i i'* and suitably fastened, as by screws *l*, and a corresponding dovetail rib *m* is attached to the surface of part *e* of the last in such relation to groove *k* that connecting part *e* to part *a* by the said rib and groove matches the parts coincidently for use practically the same as a solid last. The instep part *b* has a dowel-pin *n* in the front end, which engages with a corresponding socket in the wall of the part *a* formed by the cut at *d*, and the rear extremity of said instep part *b* is detachably secured by a screw *o* entering a screw-tapped hole in the part *j'* of the angle-plate, this connection being forward of the joint by which the sole and heel parts are connected, so that with the rear

extension *h* of part *b* overlapping the upper end of heel part *e*, as before described, all the parts of the last are rigidly joined practically as substantially as in a solid last.

The several parts *a*, *b*, and *c* of the last have the usual transverse holes *p* for connecting the hook used for pulling the last out of the finished shoe.

The lower extremity of the dovetail rib *m* on the heel part *e* lodges against the lower wall of the recess *i* in the part *a* to gage the two parts so as to match properly, and the overlapping extension *h* of the instep part *b* on the top of the heel part locks the parts *c* and *e* in their proper relation for use.

The construction is manifestly simple and cheap, and the mode of operation is obvious and also manifestly simple.

It is to be noted that the joint of the sole part and heel part is located as near to the heel of the last as is practicable for utilizing the removable heel part as a slackening device to relieve the stresses and free the last for ready removal from the shoe, and this enables the location of the screw to be so close to the rear extremity of the instep part that its power to hold the heel part from it is greater than if located farther forward, and such arrangement is manifestly more reliable than a tongue-and-groove connection of the instep and sole parts, which must at the best be sufficiently slack to work with some degree of freedom and will wear slack and unsatisfactory in use.

What I claim as my invention is—

The combination in a sectional shoe-last, of the sole part *a*, having the instep-recess, and the sloping rear end, and also having the groove *i*, *i'*, in said end and recess; the angle-plate *j*, *j'* provided with the dovetail groove *k* lengthwise in the part *j* and fitted in said groove *i*, *i'*, the heel part *e* of the last having the dovetail rib *m* adapted to fit the groove *k*, the instep part *b* of the last fitted in the instep-recess of the sole part, and the screw *o* connecting the rear extremity of the instep part with the sole part by screwing into the part *j'* of the angle-plate attached to the rear end and top of the sole part *a*.

Signed at New York city this 4th day of April, 1901.

NILS F. HAGSTRÖM.
